No. 10,050.

PATENTED SEPT. 27, 1853.

C. SLEPPY.
MAKING CHAINS.

UNITED STATES PATENT OFFICE.

CHRISTIAN SLEPPY, OF WILKESBARRE, PENNSYLVANIA.

MAKING CHAINS.

Specification of Letters Patent No. 10,050, dated September 27, 1853.

To all whom it may concern:

Be it known that I, CHRISTIAN SLEPPY, of Wilkesbarre, Luzerne county, State of Pennsylvania, have invented a new and Improved Mode of Making Chains of Iron or Any other Hard Substance; and I do hereby declare that the following is a full and exact description thereof, reference being had to the accompanying drawings and 10 to the letters of reference marked thereon.

The nature of my invention consists in making chains as joined by a machine, more fully specified hereafter.

To enable others skilled in the art to make 15 and use my invention I will proceed to describe its construction and operation.

It consists of four rollers (3) running upon journals in boxes (2) fastened in a frame work (1) each roller having cogs by 20 which they are propelled. To one of which the motive power is attached or may be to two or more. On the edge of each roller are steel dies (4) with sharp edges, corresponding to the size of the chain to be 25 forged. The dies on the several rollers converge to a point, and in passing each other,

make the chain. The rod designed to pass through the rollers, may be round or square, with four flanges to suit the guide (5) and which passes through the guide and is seized 30 at the intersection of the four rollers: passes through, and comes out on the opposite side a forged chain. The rod must be at a red heat.

The figures refer to the draft accompanying.

What I claim as my invention, and desire to secure by Letters Patent, is—

The forging and making chains out of a solid bar without the welding process; and 40 which is done instantly as the bar passes between four rollers with dies on the edges of the same molding the links into form, and which may be done out of iron, brass or any substance suitable to be used as a 45 chain, from the size of a cable to a watch guard.

August 29, 1853.

CHRISTIAN SLEPPY.
